Primary Examiner — Philip S Hyder*Assistant Examiner* — Roselynne Cody(74) *Attorney, Agent, or Firm* — Greenberg Traurig LLP(57) **CLAIM**

The ornamental design for a maul, as shown and described.

DESCRIPTION

FIG. 1 is a perspective view of an embodiment of my design; FIG. 2 is a front view thereof; FIG. 3 is a rear view thereof; FIG. 4 is a right view thereof; FIG. 5 is a left view thereof; FIG. 6 is a top view thereof; and, FIG. 7 is a bottom view thereof.

The broken lines in the drawings depict features of the maul that form no part of the claim.
